Letters Patent No. 78,496, dated June 2, 1868.

IMPROVEMENT IN CAPS FOR MARINE-STOVE PIPES.

The Schedule referred to in these Letters Patent and making part of the same.

TO ALL WHOM IT MAY CONCERN:

Be it known that I, GEORGE WARNER, of the city of Cleveland, in the county of Cuyahoga, in the State of Ohio, have invented a new and improved Cap for Marine-Stove Pipe, which is to prevent cook and other stoves used on board vessels from smoking; and I do hereby declare that the following is a full and exact description thereof, reference being had to the accompanying drawings, and to the letters of reference marked thereon.

Figure 1 is a perspective view, and

Figure 2 is a section of the same.

The same letters refer to like parts.

Letter A is a sheet-iron cap, with a conical or flat top, as may be desirable, and with an opening on one side, for the smoke to escape. The letters B B are two flexible shields, attached, by hinged joints, to each side of the opening in the cap. The letter C is a top shield, firmly attached to the cap above the opening, and made to press upon the top of side shields B B; thereby retaining them in any position desired. The outer edge of this shield may be corrugated, thereby giving greater firmness to the shields. The letters D D are two handles, used to adjust the cap to any desired position. The letter E is a flat cast-iron ring, with a projecting flange, F. This ring is fastened to the deck G, and serves to hold the stove-pipe, from below, but not shown in the drawing. The projecting flange F is used to hold the cap A in proper connection with the stove-pipe.

I construct my cap of sheet iron, and in a manner familiar to all mechanics who are accustomed to make stove-pipe and other constructions which require similar mechanical manipulation.

The general operation or adjustment of my cap is secured by hand. The necessity for this is owing to the fact that most of the stoves on board sailing-vessels are placed nearly under some of the fore-and-aft sails. The wind, when it strikes these sails, is forced downward, which, of course, would carry the smoke with it, through the stove-pipe, into the cook's room, or into the cabin, as the case may be. Hence, any device which depends upon the force of the wind, by the means of a weather-vane, to place the smoke-cap in a proper position to cause the smoke to freely escape will fail.

If I wish to have my cap adjusted by means of a weather-vane, I can do so by a spindle passing up from the stove-pipe, and reaching the cap in the apex of the conical top. In this case, the cap should be made some larger than the pipe below, in order that it may turn easily; but, as I before said, its general adjustment is by hand. The two handles D D serve for this purpose. It must not be very high above the deck, otherwise it would be in the way of the proper management of the sails; and, indeed, it frequently happens that the cap has to be taken temporarily from its place, in order to handle the sails. The use of my smoke-cap does away with the heavy basket-made guards which are placed over the top of the stove-pipes.

In consequence of the before-mentioned fact of the downward course of the wind when it strikes the sails, I use the top shield C, with a downward inclination, and projecting some little distance from the top of the opening in the cap, whereby I cause the wind to force the smoke from out of the stove-pipe. I attach the smoke-cap to the projecting flange F in such a manner that the direct current of wind will strike it on its closed side. This position should cause the smoke to be discharged freely through the opening; but, in consequence of the wind striking so many impediments on the vessel, such is not the fact. I have, therefore, attached, by hinged joints, to the side of the opening in the smoke-cap, the side shields B B. These shields are held in any desired position by the pressure of the top shield upon their top edges; and, when the front edge of the top shield is corrugated, it helps to hold the side shields more firmly in their places. It is not necessary always to place these side shields in line with the direct current of wind, but they should be so adjusted as to cause the wind to pass by the opening, and, of course, to the smoke along with it. Thus, by having a smoke-cap adjustable by hand, I can provide against any and all contingencies of working the sails. With the top shield and the two side shields, I can govern all and every current of wind, so as to prevent the smoking of cook or other stoves used on board vessels.

I disclaim a cylindrical smoke-cap or wind-guard for stove-pipes, for this is common; nor do I claim any of the usual appendages made use of in constructing the head of a wind-sail; but

What I do claim, and wish to secure by Letters Patent, is—

The top shield C and the two flexible side shields B B, in combination with the cap A, as described, and when used in the manner and for the purposes set forth,

GEORGE WARNER.
